UNITED STATES PATENT OFFICE.

HARRY H. LINDEMUTH, OF MOUNT JOY, ASSIGNOR OF ONE-HALF TO PETER L. KREISS, OF FLORIN, PENNSYLVANIA.

STEAM-GENERATOR.

SPECIFICATION forming part of Letters Patent No. 398,267, dated February 19, 1889.

Application filed May 18, 1888. Serial No. 274,293. (No model.)

To all whom it may concern:

Be it known that I, HARRY H. LINDEMUTH, a citizen of the United States, residing at Mount Joy, in the county of Lancaster and State of Pennsylvania, have invented a new and useful Improvement in Steam-Generators, of which the following is a specification.

My invention relates to an improvement in steam-generators; and it consists in the peculiar construction and combination of devices that will be more fully set forth herein-after, and particularly pointed out in the claim.

In the accompanying drawings, Figure 1 is a vertical central sectional view of a gas-burning steam-generator embodying my improvement. Fig. 2 is a horizontal sectional view of the same, taken on the line *x x* of Fig. 1.

A represents the base-casting, which forms a truncated cone, as shown, and is provided at its upper edge with an outwardly-extending depending curved flange or lip, B.

C represents a cross-bar, which has its ends turned downward to form lips or lugs and secured to diametrically-opposite sides of the base-casting by means of bolts. In the center of the said cross-bar is a circular depending boss and a vertical opening in which is journaled a depending spindle, D, of a grate, E.

F represents a grate-frame, which is annular in shape and inclines downward and inward and has its upper edge resting in the upper end of the base-casting A. Said grate-frame is provided with a series of depending lugs, G, which are bolted to the casting A, and is further provided at suitable regular distances with vertical slots H, the function of which is to admit air to the fire-box.

I represents the fire-box, which is cylindrical or oval in shape, as may be preferred, and is arranged above the grate-frame, has its lower edge resting thereon, and is provided with a door, K, through which fuel may be supplied to the fire. To the upper portion of the shell of the fire-box, which is made of boiler-iron, is bolted or riveted the lower edge of a flue-sheet, L, which extends inward over the fire-box and partly covers the same and is then turned upward, as shown.

M represents a gas-chamber, which comprises a sheet, N, having its lower end ar-

ranged within and bolted or riveted to the flue-sheet L, and a dome or crown sheet, O, which is concavo-convex, as shown, and has its lower edge bolted to the inner side of the sheet or shell of the upper end of the latter.

P represents the boiler sheet or shell, which has its lower edge arranged on the flange or loop B at a suitable distance beyond and concentric with the fire-box, a ring, R, being interposed between the lower ends of the fire-box and boiler sheet or shell and secured thereto by bolts or rivets S. On the outer side of the boiler is a sheet, T, of non-conducting material, and on the outer side of said sheet is a casing, U, of wood, which is secured thereon by means of encircling bands of brass, iron, or steel.

V represents the crown-sheet of the boiler, which is formed with a steam-dome, W, at its center, and above the said crown-sheet at a suitable distance is a dome, X, a hot-air space or chamber, Y, being thereby formed between the dome X and the crown-sheet V.

Z represents a series of vertical tubular flues which extend through and connect the flue-sheet L and the crown-sheet V and arranged concentrically with the gas-chamber M.

In the center of the crown-sheet X is an opening, A', for the attachment of a pipe or flue for the products of combustion.

B' represents a steam-escape pipe, which extends downward through the crown-sheets X and V, is then extended inward horizontally nearly to the center of the boiler, and has its inner end extended upward under the center of the dome W and to within a slight distance thereof.

A water-supply pipe, C', communicates with one side of the boiler near its base, and circulating-pipes D' E' communicate with the base and upper end of the boiler, respectively, and are adapted to be connected the one to the radiating-coils, (not shown,) to collect the waters of condensation, and the other to the safety-valve and steam-gage. (Not shown.)

The operation of my invention is as follows: The gases arising from the burning fuel in the fire-box pass upward into the gas-chamber M, strike against the dome thereof, and are deflected downward along the sides of the

gas-chamber, and are thus held above the fire-box and exposed to the fiercest heat until the gases and all of the combustible matter are consumed. The heat and incombustible material pass from the gas-chamber M upward through the flues Z into the hot-air chamber Y, and from thence escape through the opening A' in the form of a colorless vapor, all of the smoke having been consumed. The water 5 in the boiler entirely surrounds the fire-box, the gas-chamber, and the flues Z, and is thereby heated by direct contact therewith, so as to cause steam to be generated with a minimum expenditure of fuel, as will be readily 10 seen. The crown of the gas-chamber causes the water which is immediately over the same to be heated very intensely, and the steam arising from the heated water is collected in the steam-dome W and is super- 15 heated by reason of the heating-chamber Y above the said dome. From the steam-dome the steam escapes through the pipe B'. Inasmuch as the upper end of said pipe is arranged in proximity to the said dome, steam 20 is taken at a point in the steam-dome where it is hottest and driest. 25

A steam-generator thus constructed is especially adapted for use in supplying steam-heating coils in building, but may be employed for running engines and other purposes. 30

Having thus described my invention, I claim—

A steam-generator having a fire-box, I, the crown-sheet L of which has an upright flange 35 around its central opening, the heated gas-chamber having its lower edge bolted within and to each flange of the crown-sheet and closed at top, the water chamber or boiler from its base up rising above the same and 40 having its top formed by the flue-sheet V, provided at its center with the integral steam-dome W, the flues Z, extending between the crown-sheet and flue-sheet, the chamber Y, to receive the products of combustion from the 45 said flues surrounding the steam-dome and discharging vertically above the same, so that there will be a constant passage of hot gases thereover, and the pipe B, receiving steam downward at its inner end from the central 50 upper part of the steam-dome, passing thence downward into the boiler and horizontally therein, and thence extending upward through the top of the chamber Y at one side, substantially as specified. 55

In testimony that I claim the foregoing as my own I have heretofore affixed my signature in presence of two witnesses.

HARRY H. LINDEMUTH.
